UNITED STATES PATENT OFFICE

ROY E. WESTBROOK, OF EMMETT, IDAHO

METHOD OF PACKING FRUIT

Application filed March 5, 1929. Serial No. 344,424.

This invention relates to the packing of fruit, such as apples, peaches, or the like, in baskets, especially round baskets, and has for its objects to facilitate and cheapen the 5 said operation by eliminating one of the steps of the methods heretofore employed; to avoid all danger of bruising or cutting the fruit, and to produce a neater package which maintains the fruit in better condition than 10 the packages in common use.

In this and previous similar methods of packing fruit in baskets, one of the results aimed at is to so proceed that the top layer of fruit in the filled basket will be regularly 15 arranged and be so maintained during the handling and shipment of the basket, so as to present the fruit in attractive shape when the basket is opened and the fruit put on display for sale. This arrangement of the 20 top layer can, of course, be performed by hand, but that requires too much time and skill. Consequently, means have heretofore been provided, in the shape of a temporary lid, top or closure for the basket, sometimes 25 called a "ring facer", having either concentric ribs and intermediate grooves or a plurality of depressions or pockets for the fruit, whereby the top layer is regularly arranged. A paper liner, temporarily surrounded by a 30 metal shell, is then placed on this ring facer and is filled with the rest of the fruit. The shell is then removed and the inverted basket is set down over the filled liner. In all previous methods, as far as I am aware, the filled 35 basket, with the temporary closure afforded by the ring facer, is now inverted or set right side up, whereupon the facer is removed and the permanent lid is applied to the open top of the basket and secured thereto.

40 In accordance with my invention, this step of inverting the basket, before the permanent lid is applied, is done away with, and the ring facer, which is of cardboard or the like and therefore quite inexpensive, remains 45 permanently in the shipping lid, in which it is placed before the top layer of fruit is filled in, so that it serves as a cushioning pad to protect said layer.

The means for carrying out my improved 50 method, and their manner of use, are illus-

trated in the accompanying drawing, in which,

Fig. 1 is a plan view of the ring facer lid liner or pad;

Fig. 2 is a cross section of the same, on 55 line 1—1 of Fig. 1;

Fig. 3 is a perspective view of the shipping lid with the pad placed therein, ready to receive the top layer of fruit;

Fig. 4 is a similar view with the top layer 60 filled in;

Fig. 5 is a side view, showing the metal shell, containing the paper liner, set in position on the lid;

Fig. 6 is a similar view with the shell removed and the liner filled with fruit, and 65

Fig. 7 is a side view showing the inverted basket lowered over the liner, preparatory to being fastened to the lid, and also showing a portion of a press I make use of in this 70 operation.

The ring facer lid liner pad is, as stated, made of cardboard, or the like, and has molded or pressed in it the concentric annular grooves 2. The lid 3 has its inwardly projecting portion or flange 4 of greater depth than is customary and receives the pad within the same. The inverted lid, containing the pad, is then placed on a support, such as the bed 5 of the press, shown in Fig. 7, and a layer of fruit, which eventually becomes the top layer in the basket, is placed on the pad, fitting in the grooves thereof in regular formation. The metal shell 6, containing the paper liner 7, is then set on the lid, fitting 80 around the flange 4. The rest of the fruit is then filled in, whereafter the shell is removed and the inverted basket is lowered over the liner and pressed down over said flange, as by the pivoted bails or loops 8, which are pulled down by means of the handle 9. The basket and lid are finally fastened together by any of the well known means. The completed package is then ready 85 for shipment. In this way, the step of inverting the basket before the lid is applied, is eliminated.

Having thus described my invention, what I claim is:

1. The method of packing fruit in baskets,

which consists in placing a ring facer pad within the flange of the inverted lid, filling said pad with a layer of fruit, setting a liner on said lid flange, filling said liner with fruit, lowering the inverted basket over said liner, and securing said basket and lid together.

5 2. The method of packing fruit in round baskets, which consists in laying the inverted basket lid upon a support, placing therein a circular pad, having concentric grooves in its upper surface, arranging a layer of fruit in said grooves, setting a metal shell, containing a paper liner, on said inverted lid, filling said shell and liner with fruit, removing said shell, lowering the inverted basket over said liner, and fastening said lid and basket together while still in inverted position.

10 In testimony whereof I have hereunto set my hand.

15 ROY E. WESTBROOK.
